UNITED STATES PATENT OFFICE

RAYMOND P. NORTON, OF ALGONA, IOWA, ASSIGNOR OF ONE-HALF TO WILLIAM A. NORTON, OF MARSHALLTOWN, IOWA

COIN-CONTROLLED MECHANISM

Application filed September 21, 1926. Serial No. 136,811.

The object of my invention is to provide a coin controlled mechanism of simple, durable and inexpensive construction, which is especially adapted to be used in connection with vending liquid fuels, such as gasoline.

A further object is to provide a coin controlled mechanism so constructed and arranged that the operation of the machine with counterfeit coins or slugs will be practically impossible.

More specifically it is the object of my invention to provide in connection with liquid fuel vending mechanism, having hand controlled means for delivering predetermined quantities of liquid, means for locking the vending machine against further action after the said predetermined quantity of liquid has been delivered, and in connection therewith means actuated by the insertion of a coin through a coin receiving slot in the casing for automatically releasing the vending mechanism when the said coin has been inserted.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a front elevation of a liquid fuel vending machine showing the manner in which my improved coin controlled mechanism is applied thereto, a portion of the front side of the vending mechanism being broken away to show the valve actuating mechanism of the vending machine.

Figure 2 is a side elevation of the same.

Figure 3 is an enlarged detail side elevation of the coin controlled mechanism, a portion of the retaining casing being shown in section.

Figure 4 is a rear elevation of the coin controlled mechanism.

Figure 5 is a front elevation of a coin controlled mechanism, a portion of the front side being broken away.

Figure 6 is a detail sectional view taken on the line 6—6 of Figure 2.

Figure 7 is a segmental portion of Figure

6, the timing and coin rejecting mechanism being shown in another position from that shown in Figure 6.

Figure 8 is a detail sectional view taken on the line 8—8 of Figure 5.

Figure 9 shows a segmental portion of Figure 8 with the coin receiving gate in another position of its movement.

Figure 10 is an enlarged, detail, sectional view taken on the line 10—10 of Figure 6.

Figure 11 is a detail, side elevation of a portion of the timing and locking mechanism.

Figure 12 is a detail side elevation of one of the cams of the timing mechanism.

Figure 13 is a detail view of another one of the cams of the timing mechanism.

Figures 14 and 15 are detail sectional views taken on the line 14—14 of Figure 8.

Figure 16 is a longitudinal sectional view of the coin testing mechanism, taken on the line 16—16 of Figure 4.

Figure 17 is taken on the line 16—16 of Figure 4, showing the testing mechanism in another position of its movement.

Figure 18 is a detail sectional view taken on the line 18—18 of Figure 11.

Figure 19 is a detail sectional view taken on the line 19—19 of Figure 1.

The numeral 10 indicates an upright cylindrical support on which the gasoline vending mechanism is mounted, said mechanism comprising a retaining tank 11 having outlet pipes 12 and 13. Each of said pipes includes a valve casing 14 in which the ordinary controlling valve is mounted, said valve being provided with valve stems 15.

Each of the valve stems 15 has an actuating arm 16, one end of each of said arms being provided with a set screw 17 designed to make operative connection with a cam 18 mounted on the shaft 19. The said shaft 19 is rotatively mounted in the vending machine casing 20 and also in the casing of the coin controlled mechanism 21. The forward end of the shaft 19 is provided with a crank 22, which provides means whereby when the said crank 22 is operated through a predetermined angle, the gasoline controlled valve will be opened, permitting the gasoline to be delivered from the tank 11 to the

discharge pipe 23 through the pipes 12 and 13, said discharge valve being moved to an open position when the crank 22 is in its downwardly extended position, as shown in Figures 1 and 2. A spring actuated catch 5 24 is provided for locking the said crank in said closed position, said crank being locked in said position against the action of a spring hereinafter described. The crank 10 22 is adapted to rotate to an angle of substantially 180°. The operation of the control valve, however, is completed in a fraction of the entire movement of said crank. The spring 25 is provided for moving the 15 control valve to an open position.

In the drawings I have illustrated two outlet pipes 12 and 13, each of which is provided with an independently controlled valve, and I have provided for each of the 20 valve operating shafts 19 a coin controlled mechanism. Each of these coin controlled mechanisms, however, is alike, except that one is designed to be operated by a coin of different value from that of the other. For 25 this reason but one of the coin controlled mechanisms will be hereinafter described.

As clearly shown in Figures 1 and 2, the casing 21 of the coin controlled mechanism is mounted adjacent to one side of the casing 20 of the vending mechanism. Said casing 30 21 comprises a front member 26, a top member 27, side members 28 and 29 and a bottom member 30. The inner surface of the side member 29 is provided near its upper 35 end with an inwardly extending lug 31 in which is provided a coin receiving slot 32. The member 31 is provided with a slide bar 33 designed to move through the slot 32 in such a manner as to close the same when in one position of its movement. That portion of the bar 33 extending through the slot 32 has a beveled face 34 so arranged that when a coin is placed in the slot 32, the bar 33 may be slid rearwardly. Means is hereinafter described for locking the said bar in its closed position while the coin is being passed through the coin controlled mechanism.

Beneath the member 31 is an inclined 50 frame member 35, having in its upper end an inclined recess 36. That portion of the frame forming the top of the recess 36 is provided with a groove 37 (see Figures 3, 6, 16 and 17), and that portion forming the 55 bottom of the recess 36 is provided with a cavity 38 in which is mounted a pivot pin 39, pivotally mounted on which is an L-shaped lever having a vertical arm 40 and a horizontal member 41. The member 60 41 is provided with a groove 42 which is vertically below the groove 37. The grooves 37 and 42 are arranged in a common plane and beneath the slot 32 so that as the coin is inserted through the slot 32 it will rest 65 within the grooves 37 and 42.

Within the slot 42 is provided a stripper plate 43, having a curvature of which the pin 39 is the center. The upper edge of the stripper plate 43 forms a bottom for the groove 42 when the member 41 is in its elevated position of movement. The width of the grooves 37 and 42 is substantially equal to that of the coin to be used in the machine. The distance between the top of the groove 37 and the plate 43 is equal to the diameter of the coin, just enough clearance being provided to permit the coin to move freely through the groove.

The arm 40 is provided with a bending bar 44 designed to rest adjacent to the inner surface of the coin, while it rests in the grooves 37 and 42, the coin being shown by dotted lines in Figure 17. The upper end of the arm 40 is provided with openings 45 and 46. The upper end of the frame 35 is provided with a rotatively mounted shaft 47 which extends through the opening 46 of the arm 40 and is rotatively mounted in a sleeve 48 slidably mounted in an opening 49 in the frame member 35, said sleeve 48 being held against rotary movement. The shaft 47 is provided with a spring 50 also mounted in the opening 49, having one end resting against the inner end of the sleeve 48. The forward end of the spring 50 is designed to engage a collar 51, said collar engaging the rear surface of the arm 40. The front end of the shaft 47 extends through the front plate 26 of the housing of the coin controlled mechanism, and has on its front end a crank 52, said crank being provided with a pointer 53. Mounted on the shaft 47 between the plate 26 and the frame member 35 is a collar 54 having a helically shaped cam 55. The collar 54 serves to limit the shaft 47 against inward movement. The rear end of the shaft 47 is provided with a head 58 carrying cam rollers 59.

Thus it will be seen that if the shaft 47 is rotated in a clockwise direction, as viewed from the right hand end of Figure 17, the head 58 will also be rotated, causing the cams 57 and the drum 56 and the sleeve 48 to be moved forwardly, causing tension to be applied to the spring 50, which in turn will slide the collar 51 and the upper end of the arm 40 forwardly. This will cause the bending bar 44 to engage the inner surface of the coin 60, causing the coin to be bent in the manner clearly shown in Figure 16. It will be seen that as the upper end of the arm 40 is moved forwardly, the free end of the member 41 is being moved downwardly and the depth of the groove 42 decreased. If a counterfeit coin is being used, which is considerably softer than the genuine coin, this bending operation will be continued until the top edge of the stripper plate 43 is even with the top edge of the groove 42, which will permit the lower edge of the coin to be thrown forwardly in the direction of the arrow in Figure 16,

and to be thrown out of operative relation with the mechanism for controlling the operation of the shaft 19 hereinafter described. The tension of the spring 50 is such that the spring will yield before the genuine coin is bent sufficiently to be thrown from the groove 42. The tension of the spring 50 should also be such that the elastic limit of the metal of the coin will not be reached, so that the coin will assume its original position as soon as the bending tension is released.

The coin 60 is retained within the grooves 37 and 42 against downward movement while the bending operation takes place by means of a stop pin 61 (see Figures 3 and 6). Said stop pin is slidably mounted and arranged transversely with the coin. The inner end of the pin 61 is pivotally connected to a lever 62, which in turn is pivotally mounted to the frame member 35. The free end of the lever 62 is designed to rest against an adjusting screw 63 mounted in the slide bar 33 (see Figure 10). By this arrangement it will be seen that as the coin is placed in the slot 32, the slide bar 33 will be moved rearwardly, causing the pin 61 to be moved to the position where it will be engaged by the coin 60, which movement is illustrated by dotted lines in Figure 10.

The front face of the cam drum 56 is provided with a forwardly projecting pin 64, which is also adjustably mounted in said cam. As the cam 56 is moved forwardly by the rotation of the crank 52 and at the time it has reached its forward limit of movement, the pin 64 will engage the free end of the lever 62, causing the rod 61 to be withdrawn and the coin released. At the same time the bar 33, which is also actuated by the lever 62, will be moved to its closed position. In this connection it should be noted that the bar 33 has been in an opened position during the time the coin is within the grooves 37 and 42.

Slidably mounted in the upper end of the frame 35 is a bar 65 having a shoulder 66 resting against the forward face of the arm 40, said bar 65 extending through the opening 45. The forward end of the bar 65 also rests against the cam 55. Said cam 55 provides means whereby the arm 40 will be returned to its initial position of movement.

Thus it will be seen that I have provided means whereby a large number of counterfeit coins and slugs may be rejected from the machine, due to the fact that they are usually made of softer material than the genuine coins. Iron washers, however, are often used in machines, which are stiffer than the genuine coins. Means has been provided for removing iron washers, which will hereinafter be described.

The lower end of the frame member 35 comprises a yoke having downwardly extending members 67 and 68. The members 68 is provided with an inwardly extending hori-

zontal portion 69. The member 68 is also provided with a horizontally and inwardly extending portion 70, said members being spaced apart and substantially parallel with each other. The inner ends of the members 69 and 70 support a vertically extending frame member 71. Said frame members are supported in the casing 21 by means of lugs 72 shown in Figure 3. The lower ends of the members 67 and 68 are designed to rotatively support the valve operating shaft 19.

Referring to Figure 18, it will be seen that the shaft 19 is formed in two sections, the adjacent ends of two sections being spaced a slight distance apart and joined together by means of a disk 73, said disk being provided with a slot 74 extending diametrically through its center. The diameter and thickness of the slot are slightly greater than the diameter and thickness of the coin to be used in the machine. Said disk 73 is provided with hub members 75 for receiving the adjacent ends of the shaft 19, said ends being rigidly secured therein. The forward one of the hubs 75 is designed to rotatively carry a disk 76, said disk having its inner surface provided with an annular groove 77. Said groove 77 is designed to support a spring 78, one end of said spring being designed to rest against a lug 79 fixed to the member 76. The other end of the spring 78 is designed to rest against a lug 80 supported by the disk 73 and extending into the groove 77. By this arrangement it will be seen that the disk 76 will be yieldably carried by the disk 73. The disks 73 and 76 are mounted between the frame members 67 and 68 in the manner clearly shown in Figure 3. The disk 76 has its periphery provided with a notch 81, while the disk 73 is provided with a notch 82. The inner face of the disk 73 is also provided with a lug 83 (see Figure 8). The central portion of the periphery of the disk 73 is provided with a serrated surface 84. The slot 74 of the disk 73 is located in alignment with the slot 32. The frame member 71 is provided with bearing members 85 designed to support a rotatively mounted vertical shaft 86, said shaft being designed to carry a coin receiving gate 87, comprising a pair of parallel side members which provide a coin receiving slot 88 between them, said slot being designed to lie in a common plane with the slots 32 and 74, and designed to receive the coin as soon as it has been released from the pin 61. One of the side members of the gate 87 is provided with an outwardly extending arm 89 designed to rest adjacent to the rear face of the disk 73 when in alignment with the lug 83, as clearly shown in Figure 8.

The vertical frame member 71 is provided with a pair of rollers 90 which serve to form a guide for a vertical bar 91, said bar being also operatively mounted in stationary guide members 92. The bar 91 is provided with an

outwardly projecting flange 93 having its outer edge provided with a serrated surface 94. The flange 93 is also mounted in a common plane with the slots 32 and 74. The upper end of the flange 93 is provided with a notch 95, while the upper end of the bar 91 is provided with a laterally and outwardly extending lug 96 as shown in Figures 8 and 11. Pivotedly mounted in the lower edges of the frame members 69 and 70 is a shaft 97 designed to support a lever 98, the upper end of which is provided with a slot 99 in which is mounted a roller 100. The periphery of the roller 100 is also serrated. The lower end of the lever 98 is provided with a link 101 which has its outer end screw threaded and extends through the lower end of the bar 71. Lock nuts 102 are provided so that the rod 101 may be adjusted therein, which in turn will adjust the angle of the lever 98 and the position of the roller 100 relative to the flange 93 and the disk 73. The surface 84 provides a back for the slot 88, while the roller 100 serves to provide a bottom for the same.

The parts are so arranged that when the coin 60 is dropped into the slot 88, its front edge will rest against the serrated portion of the disk 73 with its bottom edge on the roller 100 and its back edge against the flange 93, the serrated surfaces having the same number of grooves to the inch as the coin so the serrations of the coin will register with the grooves of the serrated surfaces of the members 73, 100 and 93. Figure 6 illustrates the position of the parts at the time the coin is dropped from the pin 61.

The shaft 97 is also designed to carry a locking lever 103 having an upwardly extending arm 104. The free end of the member 103 is provided with a forwardly extending lug 105 designed to enter the notch 81 of the disk 76. The free end of the lever 103 is also provided with a spring actuated dog 106 designed to enter the notch 82 of the disk 73. The upper end of the arm 104 is provided with an inwardly extending lug 107 designed to enter the notch 95 of the bar 91 when the said bar is in its elevated position of movement. The upper end of the arm 104 is also provided with a cam 108 having a beveled surface 109 designed to actuate a bar 110 mounted on the upper end of the shaft 86. A spring 111 is provided for yieldably supporting the upper end of the arm 104 to its inner limit of movement with the free end of the lever 103 at its upper limit of movement. A spring 112 is provided for retaining the gate 87 to a position with the slot 88 in alinement with the slot 74.

Secured to the lower edge of the frame member 70 is a lug 113 to which is pivoted a magnet supporting bar 114 having at its upper end a yoke 115 in which is mounted a bar magnet 116, said magnet being adjustably mounted therein by means of a set screw

117. One end of the magnet lies adjacent to the path of travel of the coin through the slots 32 and 88. A spring 118 is provided for yieldably supporting the magnet to its inner limit of movement. The support 114 is provided with a horizontally arranged bar 119 (see Figure 3), the inner end of which is provided with a downwardly extending lug 120. The lug 120 is designed to be supported normally in the path of the cam 121 mounted on the disk 122, said disk being rigidly secured to the shaft 19.

The operation of my device is as follows: The operation of the device for testing the resiliency of the coin has already been described, which is operated through the lever 52. The coin 60 is delivered to the slot 88 of the gate 86. Assuming that the coin is non-magnetic, then it will be delivered to the position shown in Figure 6. The operating arm 22 rests normally in its lower limit of movement and within the latch 24. The initial operating position, however, of this lever, as far as the coin tester is concerned, starts with the lever 22 in its upper limit of movement, as shown in the right hand unit of Figure 1. When the said lever is in an upright position, the disk 73 will be in the position shown in Figure 6. The lever 22 will then be rotated in an anti-clockwise direction, causing the disk 73 to be rotated, which in turn will cause the coin 60 to be rotated and the bar 91 elevated, due to the meshing of the teeth of the corrugated surfaces. If the coin is genuine, then the bar 91 will be elevated until the slot 95 is in alinement with the lug 107, at which time the notches 81 and 82 will also be in alinement with the lug 105 and the pawl 106. The spring 111 will then cause the lug 107 to enter the notch 95 and the lug 105 and the pawl 106 to enter their respective notches. The upper end of the arm 104 will also pass beneath the lug 96, to positively lock the bar 91 against downward movement. This will take place after the crank 22 has been rotated through an angle of approximately 90°, or until the opposite end of the serrated surface 84 is in engagement with the coin. The inward movement of the upper end of the lever 104 will cause the cam 108 to be moved inwardly, which in turn will move the adjacent end of the bar 110 rearwardly, which in turn will cause the free end of the gate 87 to be moved rearwardly to the position shown in Figure 9, at which time the arm 89 will disengage the lug 83. The rearward movement of the gate 87 will cause the coin to be delivered to the rear side of the disk 73 and to be disengaged from the roller 100, thereby permitting the coin to drop to the interior of the casing 21.

It should be noted that at this point of the operation the set screw 17 of the valve actuating arm 16 has not reached its upper limit

of movement. In fact, when the disk 73 is in the position shown in Figure 11, and at the time the coin is being discharged from the gate, the gasoline valve is in a closed position, so that further movement of the crank 22 is necessary in order to open the gasoline valve. This is permitted by disengagement between the lug 83 and the arm 89 above described. A further movement of the arm 22 will cause the valve to be opened and gasoline delivered in any desired quantities, the crank being moved into engagement with the latch 24, which provides means for automatically retaining the valve in an open position until the measured quantity of gasoline has been delivered.

Referring to Figure 11 it will be seen that the lug 105 is still retained within the notch 81. Movement of the shaft 19, however, is permitted due to the presence of the spring 78 within the slot 77. The disk 76 is held stationary while the disk 73 is permitted to rotate. The spring 78 serves to automatically close the valve in case the operator should accidentally let loose of the crank before the entire amount of the measured quantity of gasoline has been delivered and before the crank 22 has been moved into the latch 24. The device may again be placed in an operative position by simply releasing the latch 24, which will close the valve, after which the crank 22 may be moved to its vertical position. When the lever is thus released, the disk 73 will rotate in a clockwise direction, as viewed in Figures 6, 7 and 11, until the notch 82 has been engaged by the lug 106, this movement being accomplished by the spring 78. A further movement of the lever 22 in a clockwise direction will cause the disk 73 to be rotated and the pawl 106 to be moved downwardly on account of its engagement with the notch 82. This will cause the free end of the lever 103 to be lowered and the upper end of the arm 104 to be moved outwardly, causing the lug 107 to disengage the notch 95, permitting the bar 91 to move to its lower limit of movement. At the same time the cam 108 will disengage the bar 100 permitting the gate 87 to be moved forwardly to its normal position with the slot 88 in alinement with the slot 36, causing the mechanism to return to its normal position of movement. The machine is then in position for a new cycle of operation, at which time a coin may be placed in the slot 32, the lever 52 operated and the coin bending mechanism operated as before described. If the coin inserted should be a slug instead of a genuine coin and provided with a smooth edge instead of a serrated edge, then the coin will be delivered to the slot 88 in the same manner as a genuine coin, the only difference in operation being that the bar 93 will not be lifted sufficiently, if at all, to permit the lug 107 to enter the notch 95 and no movement

would be imparted to the gate 87, the machine being locked against any further movement with the exception that the slot 74 will be moved into alinement with the coin as shown by dotted lines in Figure 7, at which time the slug will pass through said slot by gravity and enter the passage 123 which leads to a receptacle 124 projecting from the side of the casing 21 for receiving the slug. An opening 125 is provided in said receptacle for the removal of the slug. Thus it will be seen that any slug having any irregularities, whereby the bar 91 is not lifted to its complete elevated position, will be delivered to the receptacle 124.

If an iron washer or slug is inserted in the slot 32, it will usually be passed to the slot 88, due to the fact that it is stiffer than the genuine coin. In this case, however, the coin passes so close to the inner end of the magnet 116 that the coin is retained adjacent to said magnet and is not delivered directly to the position of the coin shown in Figure 6. The shaft 19 is rotated in the usual manner which will cause the cam 121 to be rotated and to engage the lug 120, thereby causing the magnet 116 to be moved inwardly and the coin stripped therefrom, due to the fact that a portion of it lies within the slot 88. The coin will then fall to the position shown in Figure 7. It must be borne in mind that the disk 73 has made a partial rotation and that the bar will only be partially elevated to its upper limit, which will result in the iron slug being delivered to the receptacle 124.

Thus it will be seen that I have provided a coin controlled mechanism which may be used in connection with vending machines, such as used to distribute gasoline, and which is positive in its action, and which has the ability to discharge a large percent of slugs or counterfeit coins, and which is adapted to be used in connection with different types of vending machines.

I claim as my invention:

1. In combination, a movable member for actuating a vending mechanism, means for locking said movable member against movement to actuate said vending mechanism, a coin controlled mechanism including a coin receiving slot, a disk rotatively mounted in a common plane with said receiving slot having its periphery serrated so that said serrated portion will mesh with the serrated edge of a coin, a movable bar having one edge serrated and designed to mesh with the serrated edge of said coin, means for rotating said disk to impart movement to said movable bar when the coin is in engagement with the serrated edges of said disk and said bar, and means actuated when said bar has been moved a predetermined amount for releasing said locking mechanism.

2. In combination, a movable member for actuating a vending mechanism, means for

locking said movable member against movement to actuate said vending mechanism, a coin controlled mechanism including a coin receiving slot and a serrated bar, means actuated by said serrated bar for releasing said locking mechanism, and hand actuated means for utilizing the serrated edge of a coin when inserted therein for imparting a predetermined movement to said serrated bar.

3. In combination, a movable member for actuating a vending mechanism, means for locking said movable member against movement to actuate said vending mechanism, a coin controlled mechanism including a coin receiving slot and a serrated bar, means actuated by said serrated bar for releasing said locking mechanism, hand actuated means for utilizing the serrated edge of a coin when inserted therein for imparting a predetermined movement to said serrated bar, and means for rejecting coins of lower resiliency than a genuine coin before they have been brought into operative engagement with said mechanism for actuating said serrated bar.

4. In combination, a movable member for actuating a vending mechanism, means for locking said movable member against movement to actuate said vending mechanism, a coin controlled mechanism including a coin receiving slot and a serrated bar, means actuated by said serrated bar for releasing said locking mechanism, hand actuated means for utilizing the serrated edge of said coin when inserted therein for imparting a predetermined movement to said serrated bar, means for rejecting a coin of lower resiliency than a genuine coin, and means for rejecting a magnetic coin of higher resiliency than a genuine coin before it has been brought into operative engagement with said mechanism for actuating said serrated bar.

5. In combination, a movable member for actuating a vending mechanism, means for locking said movable member against movement to actuate said vending mechanism, a coin controlled mechanism for releasing said locking mechanism and including a coin receiving slot terminating in a pair of parallel guide members spaced apart a distance equal to the diameter of the coin, said guide members being provided with grooves for retaining the coin against transverse movement, a bending bar located adjacent to one side of the coin when in said guides and substantially parallel therewith, yieldable means for imparting pressure to said bending bar, and means for discharging the adjacent edge of said coin from said grooves when the coin has been bent beyond a predetermined amount.

6. In combination, a rotatively mounted shaft for actuating a vending mechanism, said vending mechanism being actuated upon a predetermined movement of said shaft,

means for locking said shaft against said predetermined movement, a coin controlled mechanism including a coin receiving slot, a disk mounted on said shaft, said disk being provided with a coin receiving slot in alignment with the first said slot, the periphery of said disk between the ends of said slot being serrated to correspond with the serrated edge of a coin, a bar having one edge serrated and mounted in a common plane with said slots, the serrated edges of said bar and said disk being arranged to receive a coin between them and to impart movement to said bar as said disk is rotated by rotating said coin, and means actuated when said disk has been moved a predetermined amount for releasing said locking mechanism.

7. In combination, a coin controlled mechanism having a coin guide and means for rejecting slugs or counterfeit coins, a disk rotatively mounted in a common plane with said coin receiving guide having its periphery serrated so that said serrated portion will mesh with the serrated edge of a coin, a movable bar for controlling said rejecting means having one edge serrated and designed to mesh with the serrated edge of said coin, and means for rotating said disk to impart movement to said movable bar when the coin is in engagement with the serrated edges of said disk and said bar.

8. In combination, a coin controlled mechanism having a coin guide and means for rejecting slugs or counterfeit coins, a disk rotatively mounted in a common plane with said coin receiving guide having its periphery serrated so that said serrated portion will mesh with the serrated edge of a coin, a movable bar for controlling said rejecting means having one edge serrated and designed to mesh with the serrated edge of said coin, means for rotating said disk to impart movement to said movable bar when the coin is in engagement with the serrated edges of said disk and said bar, a second serrated disk supported between the first disk and said movable bar, and means for adjusting the position of the second disk relative to the first disk and movable bar.

9. In a device of the class described, a coin testing mechanism, a coin guide for conveying coins to said testing mechanism and to a coin controlled mechanism, means actuated by the insertion of a coin in said guide for stopping said coin in said guide in operative relation with said testing mechanism, and means for automatically releasing said coin after the testing operation is complete.

10. A coin controlled device comprising a pair of guide members spaced apart a distance equal to the diameter of the coin, said guide members being provided with grooves for retaining the coin against transverse movement, a bending bar located adjacent to one side of the coin when in said grooves and

substantially parallel therewith, yieldable means for imparting pressure to said bending bar, and means for discharging the adjacent edge of said coin from one of said grooves when the coin has been bent beyond a pre-determined amount.

11. A coin controlled mechanism comprising a pair of parallel guides spaced apart a distance equal to the diameter of a coin, said 10 guides having grooves for retaining the coin against transverse movement, means for applying transverse pressure to the center of a coin while in said grooves for bending the same, and means for discharging the adjacent edge of said coin from one of said grooves when the coin has been bent beyond a pre-determined amount.

Des Moines, Iowa, July 21, 1926.
